LIQUID SOAP DISPENSER

Simon Yerkovich, Los Angeles, and John A. T. Rathbone, Culver City, Calif., assignors of one-half to Myco Industries, Inc., a corporation of California, and one-half to Jet Dispenser Corp., a corporation of California

Filed Oct. 26, 1964, Ser. No. 82,313

Term of patent 14 years

(Cl. D4—3)

We claim:

The ornamental design for a liquid soap dispenser, as shown and described.
